UNITED STATES PATENT OFFICE.

HENRY W. WAGENET, OF OAKLAND, CALIFORNIA.

SWEAT-SHIELD FOR HATS.

No. 900,330.

Specification of Letters Patent.

Patented Oct. 6, 1908.

Application filed March 6, 1907. Serial No. 360,974.

To all whom it may concern:

Be it known that I, HENRY W. WAGENET, a citizen of the United States, residing at Oakland, in the county of Alameda and State 5 of California, have invented new and useful Improvements in Sweat-Shields for Hats, of which the following is a specification.

The object of the present invention is to provide a cheap and simple device which can 10 be quickly attached to the interior sweat band of an ordinary hat, which will effectually shed the perspiration, and prevent it passing through to the outside of the hat, dis- coloring the same.

15 In the accompanying drawing, Figure 1 is a broken view of a hat equipped with my im- proved shield; Fig. 2 is an enlarged sectional view of the same.

Referring to the drawing 1 indicates the 20 body of a hat, having a hat band 2, and an interior sweat band 3, the latter stitched to the hat at the lower edge, as shown at 4.

5 indicates my improved protector, which is made of celluloid or material which can be 25 made in very thin sheets and is absolutely water proof. It is preferably made suffi- ciently long to reach about half way around, it being generally necessary to protect only the front portion of the hat, next the fore- 30 head. However, it may be made of a length to extend over the full circumference of the sweat band, if desired. The protector is at- tached to the upper edge of the sweat band, by devices which will permit of quickly at- 35 taching or detaching the same. I here show it as attached by means of small metallic clips 6, such as are commonly used to fasten together sheets of paper. The lower edge of the protector extends slightly below the line 40 of stitches 4 which connects the sweat band with the hat. This is a feature of extreme importance, as the so-called sweat band af- fords very little protection to the body of the hat against permeation therein of the perspi- 45 ration from the forehead, for the reason that the perspiration runs down to the line of stitches and then the threads, acting as ducts, convey the perspiration to the body of the hat, which perspiration is thus absorbed 50 thereby in ever increasing quantities, thus ruining the appearance of the hat. But, by attaching the shield to the upper edge of the sweat band and permitting its lower edge to extend below the line of stitches of said

sweat band, the perspiration is effectually 55 prevented from obtaining access to said stitches. The lower edge of the protector is turned or crimped slightly outwards as shown at 7, so as to rest comfortably on the forehead. 60

I am aware that it has been proposed to reinforce the ordinary sweat band by an ad- ditional sweat band of leather, cemented to the leather sweat band, and extending over the line of stitching, to the hat of the ordi- 65 nary sweat band. While such construction is in a certain degree advantageous in pro- longing the time during which the hat re- mains uninjured by the sweat of the wearer, yet it does not afford absolute protection 70 against such injury or discoloration, as the sweat will eventually force its way first, through the second sweat band, and then through the first, or through the line of stitches. Moreover, being made of leather, 75 it is necessarily of considerably greater thickness than when made of celluloid. But the principal advantage which my in- vention possesses over said prior art is that it permits of the devices being placed upon 80 the market and sold entirely separate from the hats, so that any person desiring to use the same, to prevent the discoloration of a light felt or straw hat, can himself quickly attach one of these devices to the hat, and 85 can also, when discarding an old hat for a new one, detach the device from the old hat and attach it to the new one.

I claim:—

In combination with a hat having a sweat 90 band stitched thereto, a strip of celluloid, shaped to conform to the shape of the sweat band and to cover any desired portion of the circumference thereof, the lower edge of said strip being bent out from the plane of the 95 strip so as to lie immediately beneath said line of stitches, and a plurality of fastening devices suitably located at different points of the strip for detachably securing said strip to said sweat band. 100

In testimony whereof I have hereunto set my hand in the presence of two subscribing witnesses.

HENRY W. WAGENET.
